UNITED STATES PATENT OFFICE.

JOHN C. McKEOWN, OF CHICAGO, ILLINOIS.

LATTICE-TRUSS.

No. 851,804.

Specification of Letters Patent.

Patented April 23, 1907.

Application filed February 26, 1907. Serial No. 369,295.

To all whom it may concern:

Be it known that I, JOHN C. McKEOWN, a citizen of the United States, and a resident of Chicago, in the county of Cook and State of Illinois, have invented certain new and useful Improvements in Lattice-Trusses, of which the following is a specification.

This invention relates to trusses, such as roof and bridge trusses, and relates particularly to lattice trusses of the familiar type comprising a curved, usually substantially circular, upper chord, a straight lower chord and crossed lattice or web members which connect said upper and lower chords at intervals between their ends and which are rigidly secured together where they cross each other. In trusses of this type it is a simple engineering problem to figure out the maximum and minimum tension and compression stresses to which the different lattice or web members will be subjected under different conditions of loading, and knowing the material of which said lattice or web members will be constructed, to make them adequately strong to carry their respective maximum loads. The lattice or web members, however, are usually larger in cross section in the plane of the truss than crosswise thereto, and, as compression stresses in said lattice or web members will produce a tendency to buckle them laterally, it is obvious that the capacity of said lattice or web members to withstand the buckling stresses to which they are subjected will determine the real resistance or strength of the truss as a whole. A member, when in tension, is obviously subjected to no buckling stress, and it is also obvious that the buckling stress in any compression member can be largely overcome by rigidly connecting it with the tension members which it crosses, or by thus connecting crossed compression members, an average buckling stress produced therein.

The primary object of my invention is to provide a truss of this general type in which the lattice or web members will cross each other at relatively short and substantially uniform intervals and in which each lattice or web member will be crossed by a relatively large number of other members, thus providing for supporting said members against lateral buckling in a very efficient manner, and without materially affecting the tension and compression stresses therein.

To this end, my invention consists in disposing the lattice or web members of the

truss at substantially uniform angles to the upper or curved chord, say forty-five degrees, instead of to the lower, straight chord in the manner heretofore common. 60

A further object of the invention is to provide a composite top chord for a truss of this type, the elements of which will be rigidly connected throughout the length of said chord, whereby the elements of said chord 65 will be flexed or bowed uniformly, thus maintaining the upper edge thereof, which receives the joists or other transverse supports, even throughout. To this end the elements of the top chord are provided with interlocking longitudinal tongues and grooves, which operate in an obvious manner to cause said elements to bend uniformly and to maintain the edges thereof even. 70

In the accompanying drawing, in which 75 my invention is fully illustrated,—Figure 1 is a side view of a roof truss embodying my invention; and Fig. 2 is an enlarged transverse sectional view of the top chord thereof, showing lattice or web members and a joist 80 in elevation.

Referring now to the drawings, in which, for purposes of concrete illustration, I have shown a truss of my invention as applied for supporting a roof, A represents the walls of a 85 building, B the roof thereof, comprising joists b, and a covering b¹, C the upper chord of the truss, D the lower chord thereof and E the lattice or web members. Both the upper chord C and the lower chord D are preferably 90 made in two sections between which the ends of the lattice or web members E are rigidly secured. Each section of the curved top chord C consists of a plurality of elements, as shown two elements 1 and 2, which are secured together by longitudinal interlocking tongues 3 on one thereof, and grooves 4 on the other, which will cause said elements 1 and 2 to bend uniformly, so that the top edges 5 thereof will be flush with each other and will 100 form an even seat for the joists b. The lattice or web members E, instead of being disposed at a uniform angle to the lower chord D, are disposed at a uniform angle, say forty-five degrees, to the top chord C, that is, to a 105 tangent to said top chord at the points where said lattice or web members are respectively secured thereto. With the lattice or web members E disposed at uniform angles to the top chord, as described, it is found that said 110 web members cross each other at substantially uniform intervals, whereas with the

lattice members disposed at corresponding uniform angles to the lower chord, the intervals between adjacent chords will vary materially, in some cases being much shorter and in other cases much longer than in my improved truss. It is also found that in my improved truss each lattice or web member will be crossed by at least one more oppositely inclined lattice or web member than in 10 a truss of the same size in which the lattice or web members are disposed at the same angles to the lower chord. Thus by securing the said lattice or web members together where they cross each other, which may be done in any desired manner as by means of bolts or spikes, it is obvious that the lattice or web members of my improved truss will be supported against lateral buckling stresses at substantially uniform intervals and at an increased number of points, as compared with 20 a substantially similar truss in which the lattice or web members are disclosed at uniform angles to the lower chord, thus effecting the object of my invention as it relates to this 25 feature.

I claim:

1. A truss comprising a curved upper chord, a lower chord and lattice members which connect said chords, said lattice members being disposed at substantially uniform 30

angles to the upper chord at their respective points of attachment thereto.

2. A truss comprising a curved upper chord, a lower chord and lattice members which connect said chords, said lattice members being disposed at angles of substantially forty-five degrees to the upper chord at their respective points of attachment thereto. 35

3. A truss comprising a curved upper chord comprising a plurality of elements provided with longitudinal interlocking tongues and grooves, a lower chord and lattice members which connect said chords, said lattice members being disposed at substantially uniform angles to the upper chord at their respective points of attachment thereto. 40

4. A truss comprising a curved upper chord comprising a plurality of elements provided with longitudinal interlocking tongues and grooves, a lower chord and lattice members which connect said chords. 45

In testimony, that I claim the foregoing as my invention, I affix my signature in presence of two subscribing witnesses, this 20th day of February, A. D. 1907.

JOHN C. McKEOWN.
